CLAIM

The ornamental design for a poolside basketball goal, as
shown and described.

DESCRIPTION

FIG. 1 is a front elevational view of a poolside basketball goal embodying our new design;

FIG. 2 is a rear elevational view thereof;

FIG. 3 is a side elevational view thereof;

FIG. 4 is a top plan view thereof; and,

FIG. 5 is a bottom plan view thereof.

The side opposite the side shown in FIG. 2, has the
same appearance as shown in FIG. 2.

FIG.1

FIG.2
